[57] CLAIM

The ornamental design for a cylinder heating cabinet, as shown and described.

DESCRIPTION

FIG. 1 is a perspective view of my design for a cylinder heating cabinet;

FIG. 2 is a front elevational view of the cylinder heating cabinet of FIG. 1;

FIG. 3 is a left side elevational view of the cylinder heating cabinet of FIG. 1;

FIG. 3 is a left side elevational view of the cylinder heating cabinet of FIG. 1;

FIG. 4 is a right side elevational view of the cylinder heating cabinet of FIG. 1;

FIG. 5 is a top plan view of the cylinder heating cabinet of FIG. 1;

FIG. 6 is a bottom plan view of the cylinder heating cabinet of FIG. 1;

FIG. 7 is a perspective view of my cylinder heating cabinet of FIG. 1 showing the interior of the cabinet with the cabinet door opened;

FIG. 8 is a perspective view of my cylinder heating cabinet of FIG. 1 which is similar to that of FIG. 7 except that a cylinder having been placed in the cabinet is also shown in dashed lines.
